DESIGN FOR A STATUETTE OR SIMILAR ARTICLE

Irving Defren, Brooklyn, N. Y.

Application April 4, 1939, Serial No. 84,036

Term of patent 7 years

To all whom it may concern:

Be it known that Irving Defren, a citizen of the United States and resident of Brooklyn, in the county of Kings and State of New York, has invented a new, original, and ornamental Design for a Statuette or Similar Article, of which the following is a specification, reference being had to the accompanying drawing, forming part thereof, in which,

Fig. 1 is a perspective view showing the side of a statuette, embodying my new design and

Fig. 2 is a perspective view showing the front thereof.

The essential features of my design reside in the specific configuration of the head and neck portions and of the harness and mane, said harness and mane being of material contrasting with that of the horse's head and the supporting base member.

I claim:

The ornamental design for a statuette or similar article, substantially as shown and described.

IRVING DEFREN.
